KNOCKDOWN TABLE OR STOOL

Leon Green, Los Angeles, Calif.

Application July 26, 1946, Serial No. 686,393

2 Claims. (Cl. 311—35)

1

My invention relates generally to stools and tables and more particularly to devices of this type which may readily be collapsed and carried from place to place for use on outings, etc.

While numerous collapsible stools and tables have previously been developed, these have generally been relatively complicated devices, or like the folding canvas stool have been sufficiently non-rigid to cause their field of usefulness to be severely restricted. Other collapsible stools and chairs, such as the well known folding chair, have been developed which have been quite simple and comparatively rigid; but these have been relatively heavy, and even in their collapsed condition have occupied a considerable amount of space.

It is therefore the major object of my invention to provide a light-weight collapsible stool which is very simple in construction and operation.

It is another object of my invention to provide such a stool which occupies a very small space when in its collapsed position, but which provides a very rigid support when it is in its erected position.

A further object of my invention is to provide a table having the same general features and advantages of my improved collapsible stool, and particularly suitable for use with the latter.

Still another object of my invention is to provide such a stool and table which may be inexpensively manufactured and may be readily produced in large quantities.

These and other objects and advantages of my invention will become apparent from the following description of a preferred form thereof, and from the drawings illustrating that form in which:

Fig. 1 is a perspective view of the forward side of my improved stool in collapsed position;

Fig. 2 is a similar perspective view of the rear side of my stool;

Fig. 3 is a side elevational view of my improved stool in erected position;

Fig. 4 is a bottom view of a table with the supporting legs removed, built in accordance with the teachings of my invention; and

Fig. 5 is a cross-sectional view of the table taken at 5—5 in Fig. 4.

From the following description of my device, it will become apparent that, with few exceptions, the principal difference between my collapsible stool and my collapsible table is one of size, the stool having a smaller seat or supporting surface and shorter legs, and the table having a larger top or supporting surface and longer legs.

Referring now to the drawings, the numeral 10 indicates a supporting surface of wood or metal, preferably circular, and provided with a pivotally attached handle 11 on the under sur-

2

face near the edge thereof. As seen in Figs. 2 and 3, the handle 11 consists of a U-shaped member having an outwardly extending ear 12 at the end of each of its arms, and these are held to the supporting surface 10 by brackets 13 which are firmly connected thereto. When the supporting device is to be carried, the handle 11 may be turned to the position shown in Figs. 1 and 2, and the fingers of the hand may be placed between the grip of the handle and the edge of the supporting surface 10. When the supporting device is in its erected position, the handle 11 hangs downwardly from the under side of the supporting surface, where it is out of the way.

15 Centrally located with respect to the supporting surface 10 is an attaching plate 14 which is held to the supporting surface in any suitable manner as by screws, rivets, or spot welding. The attaching plate 14 is preferably formed of metal, and has a plurality of sockets 15, three being a preferred member, attached to its under surface by welding; and each of the sockets is adapted to receive a detachable leg 16 which fits therein and is held by releasable means such as a bayonet 20 catch, screwthreads, or other suitable means. As indicated in Fig. 3, the sockets 15 are adapted to hold the legs 16 so that the latter extend downwardly and slightly outwardly to provide a firm support for the supporting surface 10, and thus 25 there is little likelihood of the supporting device being tipped over under normal conditions of use. While the sockets 15 may be attached directly to the underside of the supporting surface 10, it is generally preferable to use the attaching plate 14, since in this way the supporting surface 10 is stiffened if the latter is formed of metal, and a weldable material is provided for attaching the sockets 15 if the supporting surface is formed 30 of wood.

35 The legs 16 are formed of wood or metal, and may be solid or hollow as desired. If the legs are formed of hollow material, such as aluminum tubing, they are preferably closed at their lower ends so that dirt and other material will not be forced up into them. The other ends of the legs are provided with fastening means such as screwthreads 17, the pins of a bayonet catch, or other suitable means cooperating with the fastening means of the sockets 15.

40 To retain the legs 16 when the supporting device has been collapsed, I provide a clamp 20 attached to the under surface of the attaching plate 14, and provide it with a screw and wing nut 21 which may be tightened to grip the legs 16 firmly. As shown in Fig. 5, I prefer to form the clamp 20 so that the individual legs are tightly and individually held, for in this way the possibility of loss of one or more of the legs is materially reduced. When the supporting device is 45 in collapsed condition, the legs 16 may be held 50

by the clamping member 20 as indicated in Fig. 2;

If the supporting device is to be a stool, the supporting surface 10 and the legs 16 will be of a size suitable for such use. If the device is to be used as a table the construction may be exactly the same but with the parts enlarged in size so that a larger supporting surface 10 is provided, and the legs 16 hold the latter farther above the ground. Normally however, a table has a top or supporting surface which is three or four feet in diameter or more, and it becomes difficult to carry a device of this size. Consequently, in Fig. 4 I have illustrated one method by which the top or supporting surface of the table may be made smaller for convenience in carrying.

As shown in Figs. 4 and 5, the supporting surface of a table formed in accordance with this design includes a central portion 10a to which leaf portions 10b are pivotally attached by hinges 22. The portions 10a and 10b may be metal or wood, but if formed of metal, it will generally be found desirable to stiffen them in some manner, such as by forming "beads" in them or by providing flanges along their edges. If these members, however, are made of wood or of a heavier gauge metal, such stiffening will not be required. A handle 11 is provided with ears 12 which fit in brackets 13, similarly to the previously described form, and an attaching plate 14 is provided with sockets 15 and a clamping member 20 having a bolt and wing nut 21. The sockets 15 are adapted to receive legs (not shown) which are held in the sockets by suitable attaching means similar to those used in the previously described form, and the legs may be removed from the sockets and held in the clamping member 20 for convenience in carrying.

It will thus be seen that the table shown in Figs. 4 and 5 is of the drop leaf style; and to support the leaves 10b in their raised position, I provide a rotatable cross bar 23 which is pivotally attached to the center portion 10a by a rivet 24 or other suitable means, and which is located between the center portion and the attaching plate 14. It will be seen in Fig. 5 that the rivet 24 holds the attaching plate to the center portion 10a, but this attachment is sufficiently loose to permit the cross bar 23 to be rotated without difficulty. To provide additional support for the attaching plate 14, I mount spacing members 25 between the attaching plate and the center portion 10a to insure that these two are held together rigidly without any possibility of wobbling. As shown, the spacers 25 are located so that the cross bar 23 may be rotated from the position where it supports the drop leaves 10b, shown in solid outline, to the position where the leaves are no longer supported and the table may be collapsed for carrying, this position being shown in phantom outline. Other forms of support for the drop leaves 10b may of course be used, but I have found the form described to be very sturdy, while possessing the advantages of ease of operation and convenience of manufacture.

To use the collapsible stool first described, the wing nut 21 is loosened and the legs 16 are removed from the clamp 20. The appropriate ends of the legs 16 are then inserted in the sockets 15, and tightened so that the legs are firmly and securely held therein. To collapse the stool, it is only necessary to remove the legs 16 from the sockets 15, replace the legs in the clamp 20, and tighten the wing nut 21. It will be noted that the handle 11 is mounted so as to be aligned with the legs 16 when the latter are held in the

clamp 20; and the center of gravity of the collapsed stool is thus immediately below the handle regardless of the position of the legs with respect to the clamp. The stool may thus be easily carried, and in fact two or more stools may be carried in each hand. The stools occupy a very small space when in their collapsed position, and consequently they may be placed in the luggage compartment of a car and carried with other outing equipment. If desired, the legs 16 may be chained together and to the attaching plate 14 to prevent one or more of them being lost, but with reasonable care in the operation of the clamp 20, such loss will be quite rare.

15 When using the collapsible table shown in Figs. 4 and 5, the legs are removed from the clamp 20 and inserted in the sockets 15 as just described. The drop leaves 10b are then raised and the cross bar 23 rotated to the position shown in 20 solid outline in Fig. 4 where it supports the drop leaves to form a flat table-top. When the table is to be collapsed, the legs are removed from the sockets 15 and placed in clamp 20; wing nut 21 is tightened; and the cross bar 23 is rotated to 25 the position shown in phantom outline in Fig. 4. The drop leaves 10b are then rotated so as to be perpendicular to the upper surface of the center portion 10a, and the table may be carried by the handle 11. However, the size of the top 30 of the table could be such that the lower edge of the center portion 10a would drag on the ground when the collapsed table is carried by the handle 11. It may thus be generally preferable to carry the table by means of the legs held in 35 clamp 20, using the handle 11 to aid in moving the table when the latter is stored in rather cramped quarters.

It will thus be seen that I have provided an improved form of collapsible supporting device 40 which has many advantages over the similar devices heretofore available. While I have shown and described a preferred form of my invention, it will be apparent that modifications may be made therein which do not in any way depart from the spirit of the invention as disclosed herein, and I do not wish to be limited to the particular form or arrangement of parts herein described and shown, except as covered by my claims.

50 I claim:

1. A collapsible supporting device such as a stool or table which includes: a relatively thin generally circular supporting element; a relatively thin generally circular reinforcing member connected to the under surface of said supporting element, said reinforcing member having a smaller diameter than said supporting element and being centered with respect thereto, thereby providing an annular margin of said supporting member without substantial reinforcement; a plurality of outwardly and downwardly extending socket members on the under surface of said reinforcing member near the edge thereof, said socket members being open at their lower ends 55 and provided with holding means; and a plurality of rigid leg members each mounted in one of said socket means and releasably engaging the holding means thereof, whereby said leg members may selectively be placed in said socket members 60 to form said supporting device, or removed therefrom to collapse said device.

2. In a collapsible supporting device such as a stool or table having a generally circular supporting element and a generally circular reinforcing member of smaller diameter than said

element and attached thereto, with means for releasably holding rigid leg members, the combination which includes: socket members for releasably holding said leg members attached to the under surface of said reinforcing member near the edge thereof and projecting downwardly and outwardly therefrom, said socket members being circumferentially spaced from each other and so arranged as to leave a diametrically extending area passing between said socket members, said area having a width equal to at least two of said leg members in side-by-side relation; and a centrally disposed releasable clamping means mounted on said reinforcing member and adapted to hold all of said leg members in parallel relationship and parallel to the plane of said supporting element, said clamping means being so disposed relative to said socket means as to confine said leg members within said area, whereby said leg members project radially beyond said socket means but without interfering therewith when said leg members are held by said clamping means.
